US00D920102S

(12) **United States Design Patent** (10) **Patent No.:** **US D920,102 S**
(45) **Date of Patent:** **** May 25, 2021**

(54) **ABSORBENT ARTICLE PACKAGE**

(71) Applicant: **The Procter & Gamble Company**,
Cincinnati, OH (US)
(72) Inventors: **Lisa June Hood**, Singapore (SG);
Sarah Patricia Kunce, Norwood, OH
(US); **Christopher Michael Keith**,
Cincinnati, OH (US); **Timothy Alan**
Burkett, West Chester, OH (US)

(73) Assignee: **The Procter & Gamble Company**,
Cincinnati, OH (US)

(**) Term: **15 Years**

(21) Appl. No.: **29/705,132**

(22) Filed: **Sep. 10, 2019**

Related U.S. Application Data

(62) Division of application No. 29/578,209, filed on Sep.
20, 2016, now Pat. No. Des. 864,715, which is a
division of application No. 29/482,137, filed on Feb.
14, 2014, now Pat. No. Des. 768,480.

(57) **CLAIM**

The ornamental design for an absorbent article package, as
shown and described.

DESCRIPTION

FIG. 1 is a perspective front view of an absorbent article
package embodying the new design;

FIG. 2 is a front view of the design shown in FIG. 1;

FIG. 3 is a right side view of the design shown in FIG. 1;

FIG. 4 is a back view of the design shown in FIG. 1;

FIG. 5 is a left side view of the design shown in FIG. 1;

FIG. 6 is a top view of the design shown in FIG. 1; and,

FIG. 7 is a bottom view of the design shown in FIG. 1.

The broken lines within the tag are claimed surface indicia;
all other broken lines depict portions of the absorbent article
package that form no part of the claimed design.

1 Claim, 4 Drawing Sheets
